JAMES KARMI DALKRANIAN, OF WEST HOBOKEN, NEW JERSEY, ASSIGNOR TO NAZAR COSTIKYAN, OF NEW YORK, N. Y.

LOOM FOR WEAVING ORIENTAL KNOT-PILE FABRICS.

1,090,692.

Specification of Letters Patent. Patented Mar. 17, 1914.

Application filed December 11, 1906. Serial No. 347,342. Renewed August 5, 1913. Serial No. 783,195.

To all whom it may concern:

Be it known that I, JAMES KARMI DALKRANIAN, a citizen of the United States, and a resident of West Hoboken, in the county 5 of Hudson and State of New Jersey, have invented a new and Improved Loom for Weaving Oriental Knot-Pile Fabrics, of which the following is a full, clear, and exact description.

10. The invention relates to pile fabric looms such as shown and described in the application for Letters Patent of the United States, No. 265,886, filed by me on June 19, 1905.
15. The object of the invention is to provide a new and improved pile fabric loom, more especially designed for weaving pile fabrics of the oriental rug type, and preferably such having Persian knots and a reinforced body, 20 as shown and described in the application for Letters Patent of the United States, No. 312,143, filed by me on April 17, 1906.

The invention consists of novel features and parts and combinations of the same, 25 which will be more fully described herein-after and then pointed out in the claims.

A practical embodiment of the invention is represented in the accompanying drawings forming a part of this specification, in 30 which similar characters of reference indicate corresponding parts in all the views.

Figure 1 is a front end elevation of the loom; Fig. 2 is an elevation of the left or rear side of the loom; Fig. 3 is an enlarged 35 rear side elevation of the actuating mechanism for the heddles, parts being shown in section; Fig. 4 is an enlarged side elevation of the weft carrier; Fig. 5 is an enlarged sectional side elevation of the loom on the line 5—5 of Fig. 1, and showing more particularly the yarn tubes for the reinforcing warp threads and their tension device and the cam mechanism for operating the same; Fig. 6 is a similar view of the same on the 40 line 6—6 of Fig. 1 and showing more particularly the actuating mechanism for the endless yarn tube carrier, and the mechanism for raising and lowering the lower comb of the shogging device; Fig. 7 is a like view of the same on the line 7—7 of Fig. 1 45 and showing more particularly the mechanism for reciprocating the shogging combs and the actuating mechanism for the release of the tuft yarn tube frames from the 50 endless carrier; Fig. 8 is a similar view of

the same on the line 8—8 of Fig. 1 and showing more particularly the actuating mechanism for the lay; Fig. 9 is a plan view of the same; Fig. 10 is an enlarged sectional side elevation of the loom on the line 10—10 55 of Fig. 1, and showing more particularly the actuating mechanism for the tuft yarn tube frames and the locking device for the endless carrier; Fig. 11 is an enlarged elevation of a portion of the right side of the 60 loom and showing more particularly the cutting mechanism for the pile threads; Fig. 12 is an enlarged front elevation of the right hand portion of the loom, parts being in section on the line 12—12 of Fig. 11, the 65 view showing more particularly the general driving mechanism and the actuating mechanisms for the weft carrier and the pile thread cutter; Fig. 13 is an enlarged front elevation of the pile cutter; Fig. 14 70 is a sectional side elevation of the loom on the line 14—14 of Fig. 1, and showing more particularly the actuating mechanism for the weft carrier and the tension device for the weft; Fig. 15 is a sectional side elevation of the loom on the line 15—15 of Fig. 75 1, and showing more particularly the selvage-forming mechanism and take-up mechanism for the cloth; Fig. 15^A is a plan view of the cam shown in Fig. 15; Fig. 16 is an 80 enlarged front elevation of the weft carrier, the selvage-forming device and the shogging device; Fig. 17 is a plan view of the same; Fig. 18 is a sectional plan view of the same on the line 18—18 of Fig. 16; Fig. 85 90 19 is a sectional side elevation of the same on the line 19—19 of Fig. 20; Fig. 20 is a front elevation of the same; Fig. 21 is a like view of the same and showing the parts in a different position; Fig. 22 is a sectional 95 side elevation of the same on the line 22—22 of Fig. 20; Fig. 23 is a cross section of the looper shuttle for the selvage-forming device, the section being on the line 23—23 of Fig. 19; Fig. 24 is a rear sectional elevation of the let-off mechanism for the warp beam; Fig. 25 is a plan view of the same; Fig. 26 is an enlarged sectional front elevation of the loom, the section being on the line 26—26 of Fig. 2, and showing more 100 particularly the tuft yarn tube frame, the endless carrier mechanism and the shogging device for the same; Fig. 27 is an enlarged 105 sectional side elevation of the tuft yarn tube frame and the endless carrier, the section 110

- being on the line 27—27 of Fig. 28; Fig. 28 is a transverse section of the same on the line 28—28 of Fig. 27; Fig. 29 is a front elevation of the same, parts of the endless carrier being in section; Fig. 30 is a sectional plan view of the same on the line 30—30 of Fig. 28; Fig. 31 is an enlarged sectional front elevation of the release mechanism for releasing the tuft yarn tube frame 10 from the endless carrier; Fig. 32 is a plan view of the same; Fig. 33 is a sectional side elevation of the same on the line 33—33 of Fig. 31; Fig. 34 is a sectional plan view of the same on the line 34—34 of Fig. 31; Fig. 35 is an enlarged sectional side elevation of 15 the breast beam and the cloth temple, the section being on the line 35—35 of Fig. 32; Fig. 36 is a sectional plan view of the front end of the loom, the section being on the line 36—36 of Fig. 1, and showing more particularly the frame for the reinforced tuft yarn tubes and mechanism for operating the same, also adjacent parts; Fig. 37 is a sectional front elevation of the same; Fig. 38 is an enlarged front elevation of 20 the loom and showing more particularly the shogging combs, the needles and the actuating mechanisms for the same; Fig. 39 is an enlarged sectional rear end elevation of 25 the loom on the line 39—39 of Fig. 2, and showing more particularly the tension device for the reinforced ground warp threads; Figs. 40, 41, 42, 43, 44, 45, 46, 47, 48, 49, 50, 51, 52, 53, 54, 55, 56 and 57 are enlarged 30 sectional side elevations of the fabric-forming devices, and illustrating the successive steps required for the formation of the fabric; Fig. 40^A is a plan view of a dent of the lay and a pair of ground warp threads, the 35 position of the parts corresponding to the one shown in Fig. 40; Fig. 41^A is a like view of the same showing the ground warp threads crossed, the position of the parts corresponding to the one shown in Fig. 41; Fig. 42^A is a similar view of a dent of the 40 lay, a tufted yarn tube and a pair of ground warp threads in crossed position, the position of the several parts corresponding to the one shown in Fig. 42; Fig. 43^A is a like 45 view of the same in a different position and corresponding to the position shown in Fig. 43; Fig. 44^A is a plan view of a dent of the lay and a pair of ground warp threads in position corresponding to the one shown in Fig. 44; Fig. 45^A is a plan view of a dent of 50 the lay, a pair of ground warp threads and a pile thread, parts being in position corresponding to the one shown in Fig. 45; Fig. 58 is an enlarged inverted distorted 55 plan view of the fabric woven by the loom; Fig. 59 is a cross section of the same on the line 59—59 of Fig. 58; Fig. 60 is a similar view of the same on the line 60—60 of Fig. 58, and Fig. 61 is a sectional perspective 60 view of the fabric.

The fabric woven by the loom.—The woven pile fabric produced by the loom and illustrated in Figs. 58, 59, 60 and 61 consists essentially of pairs of pile carrying ground warp threads *a*, *a'* flanked by non-pile carrying reinforcing warp threads *b*, *b'*, and on the said ground warp threads *a*, *a'*, are looped pile threads *c* in the form of Persian knots; that is, each pile thread is looped completely around the ground warp thread *a'* and is passed under the other ground warp thread *a*, one of the pile ends extending up on the outside of the ground warp thread *a*, and the other pile end extends up between the ground warp threads *a*, *a'*, 70 as plainly illustrated in the figures referred to. The pile threads *c* are arranged in transverse rows, and each row of pile threads *c* is bound in place in the front by a set of double binding wefts *d*, *e* and in the rear by a set of double binding wefts *d'*, *e'*. The binding weft threads *d*, *d'* are interwoven with the ground warp threads *a*, *a'* and *b*, *b'*, and the supplemental or reinforcing double weft threads *e*, *e'* are interwoven with the 75 non-pile carrying reinforcing warp threads *b*, *b'* to render the body of the fabric extremely strong and durable, at the same time protecting the loop portions of the pile threads. The weft threads *e*, *e'* are approximately in vertical alinement with the corresponding binding weft threads *d*, *d'*, as plainly shown in Fig. 61, so that the reinforcing warp threads *b*, *b'* and the reinforcing weft threads *e*, *e'* practically form 80 the back of the fabric. As shown the reinforcing weft threads *e*, *e'* pass over the non-pile carrying warp threads *b*, *b'* when the latter are in a lowermost position and pass under the non-pile carrying warp threads *b*, *b'* when the latter are in a raised position, as will be readily understood by reference to Figs. 58, 59, 60 and 61. 85

In weaving the fabric on the loom the pile ends extend downward while the back of the fabric is on top, that is, the fabric is woven in an upside down position. The several threads in the distorted Fig. 58 are shown drawn apart so as to illustrate more clearly the interweaving of the threads. 90

General construction.—The loom is mounted on a suitably constructed main frame A, and on the rear of which is journaled the warp beam B, from which unwind the ground warp threads *a*, *a'* extending forwardly and passing through the heddles C, C' (see Figs. 5 and 40-57), the reed D, the shogging combs E, E' of the shogging device and the lay F to the fell of the fabric *f*, which latter passes under the 95 breast beam G and over a roller G', then over a main frame beam A' down around a cloth beam H to finally pass over a presser roller H' employed for holding the fabric in contact with the spikes of the cloth beam H. 100

(see Fig. 7). The non-pile carrying reinforcing warp threads b , b' unwind from the warp beam I (see Fig. 5) are then engaged by tension devices I' , I^2 and then pass through the open extension portions C^2 , C^3 of the heddles C, C' and over guide rods A^2 — A^2 on the main frame A, to then pass through intermittently up and down moving yarn tubes J, J' and through the lay F to the fell of the fabric f. For each third pick a different set of pile threads c is used, each set of pile threads c being carried by a set of tuft yarn tubes K, and each set of tuft yarn tubes K is held on a frame K' 10 movably mounted on an endless carrier K² (see Fig. 2) of the usual construction and common in Axminster looms, so that further description of this part of the loom is not deemed necessary, it being understood, 15 however, that for each third pick the frame K' and its set of tuft yarn tubes K is disconnected from the carrier K² and transferred to the actuating device L for moving the set of tuft yarn tubes K in a longitudinal as well as in an up and down direction during the formation of the Persian knot, as hereinafter more fully described. 20 After the row of Persian knots is formed by this set of tuft yarn tubes K, the latter 25 and its frame K' are returned to the carrier K², after which the carrier K² is caused to travel to move the following frame K' and its set of tufted yarn tubes K into position for removal from the carrier K² to the 30 actuating device L, the said carrier K² traveling in unison with the movement of the loom.

Two separate threads d^2 and e^2 are employed for forming the double weft threads 40 d , d' and e , e' , and the said threads d^2 and e^2 pass through the eyes of two needles N, N' mounted to reciprocate intermittently in a transverse direction, to carry the threads through the open shed, the said needles N, 45 N' operating in conjunction with a selvage-forming device O located on the left side of the loom (see Figs. 2 and 15-23).

The pile threads c after a row of Persian knots have been formed are cut off at the 50 under side of the fabric by a pile thread cutter P mounted to reciprocate intermittently in a transverse direction, and when at rest is located at the right side of the machine adjacent to the needles N, N' of the 55 weft carrier.

The several mechanisms of the loom are actuated in the proper sequence from a main shaft Q extending transversely and journaled in suitable bearings in the main frame 60 A, the said shaft Q being connected in the usual manner by a manually controlled clutch mechanism with a pulley Q' connected by a belt Q² with other machinery. The rotary motion of the main shaft Q is 65 transmitted to a cam shaft Q³ extending

transversely and journaled in suitable bearings on the main frame A, and for this purpose the main shaft Q is provided with a pinion Q⁴ (see Fig. 14) in mesh with an intermediate gear wheel Q⁵ secured on a 70 short shaft Q⁶ journaled on the main frame A and carrying a pinion Q⁷ in mesh with a gear wheel Q⁸ secured on the cam shaft Q³, so that when the shaft Q is rotated a continuous but slow rotary motion is given 75 to the said cam shaft Q³ carrying the cams for actuating the various devices in the proper sequence, as hereinafter more fully described.

The manually controlled clutch mechanism above mentioned consists of a clutch member Q⁹ mounted to slide on and to turn with the main shaft Q and adapted to be moved in or out of engagement with a clutch member Q¹⁰ on the pulley Q'. The clutch member Q⁹ is engaged by a shifting lever Q¹¹ fulcrumed on the main frame A and connected by a link Q¹² with an arm Q¹³ secured on a rock shaft Q¹⁴ extending longitudinally and journaled in the main frame 90 A. The forward end of the shaft Q¹⁴ is pressed on by a spring Q¹⁵ and is provided with a hand lever Q¹⁶ under the control of the weaver and extending in a notched guideway Q¹⁷ on the main frame A. Now 95 when the hand lever Q¹⁶ is shifted the clutch member Q⁹ can be thrown in or out of mesh with the clutch member Q¹⁰ to start or stop the loom. The spring Q¹⁵ serves to hold the shaft Q¹⁴ and the clutch members Q⁹, Q¹⁰ 100 in a non-active or disengaged position.

In detail the construction is as follows:

The warp beam B.—The warp beam B (see Figs 2, 11, 14, 24 and 25) has its shaft B' removably journaled in suitable bearings on the main frame A, the said shaft B' being engaged and held against accidental displacement by the usual locking plates B² removably secured to the main frame A. Thus by the arrangement described, a warp beam with the ground warp threads a, a' thereon can be readily placed in position on the loom frame or removed therefrom whenever it is desired to do so. On the shaft B' is secured a worm wheel B³ in 110 mesh with a worm B⁴ secured on a vertically disposed shaft B⁵ journaled in suitable bearings arranged on the main frame A, and on the said worm shaft B⁵ is secured a ratchet wheel B⁶ adapted to be engaged by a pawl B⁷ held on an arm B⁸ fulcrumed loosely on the worm shaft B⁵ and pivotally connected by a link B⁹ with the upper end of a lever B¹⁰ fulcrumed at B¹¹ on the main frame A. On the lever B¹⁰ is journaled a friction roller B¹² in peripheral engagement was a cam B¹³ secured on the cam shaft Q³, and the said lever B¹⁰ is pressed on by a spring B¹⁴ to hold the friction roller B¹² in 115 engagement with the cam B¹³. Now when 120

the loom is running and the cam shaft Q³ rotates, its cam B¹³ imparts an intermittent swinging motion to the lever B¹⁰ twice for every revolution of the cam shaft Q³, and the swinging motion given to the lever B¹⁰ is transmitted by the link B⁹ to the arm B⁸ carrying the pawl B⁷, for the latter to turn the ratchet wheel B⁶ whenever the pawl B⁷ is in engagement with the ratchet wheel. The pawl B⁷ is held temporarily out of engagement with the ratchet wheel B⁶ by resting and traveling on top of a shield B¹⁵, fulcrumed loosely on the worm shaft B⁵ and pivotally connected by a link B¹⁶ with an arm B¹⁷ secured on a transversely extending shaft B¹⁸ journaled on the main frame A. On the shaft B¹⁸ are secured arms B¹⁹ carrying weights B²⁰, and a rod B²¹ located directly above the shaft B¹⁸, and a similar rod B²² is held on the main frame A a distance below the shaft B¹⁸. Now the ground warp threads a, a' as they unwind from the warp beam B extend upward and pass over the rear of the rod B²² then over the front of the shaft B¹⁸ then over the rear and top of the rod B²¹ to then pass to the heddles. Now by having the weighted arms B¹⁹ carrying the uppermost rod B²¹, it is evident that the desired tension is given to the ground warp threads a, a', and when the machine is running and the ground warp threads a, a' are pulled forward by the fabric f being drawn forward by the cloth beam H, then the pull exerted by the ground warp threads a, a' against the rod B²¹ causes a forward swinging of the arms B¹⁹, so that the shaft B¹⁸ is rocked, and the arm B¹⁷ by the link B¹⁶ pulls on the shield B¹⁵ so as to swing the same rearwardly to allow the pawl B⁷ to engage the ratchet wheel B⁶ with a view to turn the worm shaft B⁵, whereby the worm B⁴ rotates the worm wheel B³ and consequently the beam B, to allow the ground warp threads a, a' to unwind from the said beam, and to permit the arms B¹⁹ to swing back to their normal position. When this takes place the shield B¹⁵ is again swung forward, so that the pawl B⁷ is held out of engagement with the ratchet wheel B⁶ for the time being, it being understood that the let-off mechanism described periodically lets off the ground warp threads a, a' as required by the formation of the fabric. The forward swinging motion of the lever B¹⁰ is limited by a suitable stop B²³, and the shaft B⁵ is preferably provided with a suitable tension device B²⁴ of the usual form, so that further description is not deemed necessary. The ground warp threads a, a' after leaving the top rod B²¹ are engaged by the usual lease rods B²⁵ held on a strap B²⁶ loosely attached to the shaft B¹⁸.

The heddles C, C'.—The heddles C, C' are mounted to slide vertically in suitable guide-

ways formed on brackets A³ attached to and forming part of the main frame A (see more particularly Figs. 1, 2, 3, 5, 36, 38 and 39), and the upper ends of the heddles C, C' are hung on links C⁴, C⁵ depending from sets of connected levers C⁶, C⁷ fulcrumed on the top cross beam A⁴ of the main frame A and connected by links C⁸, C⁹ with levers C¹⁰, C¹¹ fulcrumed on the main frame A (see Fig. 3) and carrying friction rollers C¹², C¹³ engaging cam grooves in the cams C¹⁴, C¹⁵ secured on the cam shaft Q³. Now when the loom is in operation and the shaft Q³ is rotated, then the cams C¹⁴, C¹⁵ impart a periodical swinging motion to the levers C¹⁰, C¹¹ which by the links C⁸, C⁹ rock the sets of levers C⁶, C⁷, whereby the heddles C, C' are moved intermittently in an up and down direction, as hereinafter more fully described. The upper portions or extensions C² and C³ of the heddles C, C' are open (see Figs. 38 and 39) for the free and uninterrupted passage of the reinforcing ground warp threads b, b', so that the up and down movement of the heddles C, C' does not affect the said reinforcing ground warp threads b, b'. The lower portions or the heddles proper are of the usual construction and carry the ground warp threads a, a', so that further description of the heddles is not deemed necessary, it being understood, however, that the heddles on rising and falling carry corresponding ground warp threads a, a' along.

The reed D.—The reed D is fixed on the brackets A⁵ above mentioned, and is shown arranged between the front heddle C' and the shogging combs E, E' of the shogging device (see Figs. 5 and 36) and the reed D serves to properly guide the ground warp threads a' and to allow a ready crossing and uncrossing of the same by the action of the shogging device, without unduly disturbing the heddles C and C'.

The shogging device.—The combs E and E' of the shogging device (see Figs. 1, 2, 5, 6, 7, 15, 16, 17, 18, 19, 20, 22, 36, 37 and 38) are mounted to slide simultaneously transversely in the opposite direction, and the lower shogging comb E' has in addition a periodic up and down movement. For the purpose mentioned, the shogging comb E is mounted to slide transversely in bearings A⁵ formed in the brackets A³, and the shogging comb E' is mounted to slide transversely in vertical elongated bearings A⁶ also formed in the brackets A³, the comb also sliding transversely in heads E² which have an up and down sliding motion in guideways A⁷ on the brackets A³ (see particularly Figs. 22 and 38). The left hand ends of the shogging combs E, E' are pivotally connected with a lever E³ (see Figs. 7, 37 and 38) fulcrumed at E⁴ on the left hand bracket A³, the pivot E⁵ of the lower shogging comb E' 130

rotates the cloth beam H to wind up the fabric f in unison with the amount woven at the time. The shaft H^9 is provided with a stop arm H^{14} adapted to engage the main frame A , and the shaft H^{10} is pressed on by a spring H^{15} so as to hold the stop arm H^{14} normally against the frame A , so that the friction roller H^{12} of the arm H^{11} is held in proper position for the action of the cams H^{13} . Springs H^{16} are connected with the pawls H^5 , H^6 to hold the same in engagement with the ratchet wheel H^6 , it being understood that when one pawl engages the back of a tooth the other pawl stands midway between the length of a tooth and hence a positive turning action is given to the ratchet wheel H^6 whenever the shaft H^{10} is rocked, and the pawls H^5 , H^6 are actuated simultaneously.

In order to prevent a return movement of the ratchet wheel H^6 , the usual weighted and spring-pressed dogs H^{17} are employed and mounted on the main frame A , to engage the teeth of the ratchet wheel H^6 .

The presser roller H' over which passes the cloth has its shaft H^{18} journaled loosely in angular guideways H^{19} formed on the sides of the main frame A , so that the roller H' can readily move upward and slightly rearward, to accommodate fabrics of different thicknesses, it being understood that the roller rotates by contact with the fabric on the cloth beam H and presses the fabric in firm engagement with the spikes on the cloth beam H , so as to insure a firm grip of the cloth beam H on the fabric f .

The warp beam I and the tension devices I', I².—The warp beam I is journaled on the main frame A, and the reinforcing ground warp threads b , b' extending from the said warp beam to the guide rods A^2 are engaged by tension devices I', I² in the form of rollers (see Figs. 5 and 39) journaled in arms I³, I⁴, respectively, secured to hubs or sleeves I⁵, I⁶, of which the hub I⁵ is mounted to turn on the sleeve I⁶, and the latter is mounted to turn on a transverse shaft L' journaled on the main frame A and forming part of the actuating mechanism L for the tuft yarn tubes K. The sleeves I⁵, I⁶ are provided with weighted arms I⁷, I⁸ to press the arm I³ and its friction roller I' upward, and to press the arm I⁴ and its friction roller I² downward, to give the desired tension to the reinforcing ground warps b , b' , as will be readily understood by reference to Fig. 5. A brake I⁹ is arranged on the warp beam I (see Fig. 2) to retard turning thereof and consequently the unwinding of the reinforcing warp threads b , b' .

The yarn tubes J and J'.—The yarn tubes J and J' for the passage of the reinforcing ground warp threads b , b' are arranged vertically and secured on frames J², J³ mount-

ed to slide vertically in suitable guideways 65 on the brackets A³ (see Figs. 5, 36 and 37). The frame J² is in front of the frame J³ and arranged next to the lay F, while the frame J³ is in front of the shogging combs E, E', as plainly indicated in Figs. 5, 36 70 and 37. The lower ends of the frames J², J³ are pivotally connected by links J⁴, J⁵ with arms J⁶, J⁷, of which the arms J⁶ are secured on a transverse shaft J⁸ journaled in suitable bearings on the main frame A, 75 the arms J⁷ are secured on a hub J⁹ mounted to turn loosely on the shaft J⁸. The shaft J⁸ and the hub J⁹ are provided with arms J¹⁰ and J¹¹, respectively, carrying friction rollers J¹², J¹³ traveling in cam grooves of 80 cams J¹⁴, J¹⁵ secured on the cam shaft Q⁸ and similar to the cams C¹⁴ and C¹⁵ for actuating the heddles C, C'. Now when the loom is running and the cam shaft Q⁸ and the cams J¹⁴, J¹⁵ are rotated then swinging 85 motions are given to the arms J¹⁰, J¹¹ to rock the shaft J⁸ and the sleeve J⁹ which by the arms J⁶ and J⁷ and the links J⁴, J⁵ impart an intermittent up and down traveling motion to the frames J², J³, so as to move the 90 yarn tubes J and J' intermittently up and down, as hereinafter more fully explained.

The tuft yarn tubes K.—The tuft yarn tubes K for the passage of a set of pile threads c, are secured one alongside the other on the frame or bar K' removably held on the endless carrier chains K², and each frame K' (see more particularly Figs. 26, 27, 28, 29, 30 and 31) is provided at its ends with bearings K³ for the shaft K⁴ of the 100 yarn spool K⁵ to turn in, the motion of the latter being retarded by a spring brake K⁶, shown at the left in Fig. 29.

The pile threads c are held on the spool K⁵ in a predetermined order according to 105 the design to be produced on the fabric, and the said pile threads c unwind from the said spool K⁵, and each passes through a corresponding tuft yarn tube K, to be carried down by the latter into the fabric and 110 formed into a Persian knot, as hereinafter more fully described.

On each bearing K³ is secured or formed a guide arm K⁷, and on each end of a frame K' is secured a spring hook K⁸, and the 115 said arm K⁷ is adapted to pass between a pair of supporting links K⁹ of the endless carrier chains K², while the hook K⁸ is adapted to hook onto the innermost link of the pair of supporting links K⁹ (see Figs. 27 120 and 28), to hold the frame K' and its tuft yarn tube K on the endless carrier chains K² and to travel with the same. The pair of supporting links K⁹ alternate with single links K¹⁰, and the endless carrier chains K² 125 formed of said links K⁹ and K¹⁰ pass around the sprocket wheels K¹¹ secured on an intermittently rotating shaft K¹² extending

- engaging an elongated slot E^6 formed in the lever E^3 to allow up and down movement of this comb E' . The lower slotted end E^7 of the lever E^3 is connected by a link 5 E^8 with a bell crank lever E^9 fulcrumed on a bracket A^8 attached to the main frame A. The bell crank lever E^9 is connected by a link E^{10} with a lever E^{11} fulcrumed on the main frame A and carrying a friction roller 10 E^{12} (see Fig. 7) engaging a cam groove in the cam E^{13} secured to the cam shaft Q^3 . Thus when the loom is running and the cam shaft Q^3 rotates, then the cam E^{13} imparts a swinging motion to the lever E^{11} which by 15 the link E^{10} rocks the bell crank lever E^9 and the latter by the link E^8 imparts a transverse swinging motion to the vertically disposed lever E^3 , so that the two shogging combs E, E' are caused to slide simultaneously in the opposite directions. 20
- The heads E^2 previously mentioned (see Fig. 38) are pivotally connected with downwardly extending links E^{14} pivotally connected with bell crank levers E^{15} connected 25 with each other by a link E^{16} , the left hand bell crank lever E^{15} being fulcrumed on a bracket A^8 and the right hand bell crank lever E^{15} being journaled on a bracket A^9 of the main frame A. 30 The left hand bell crank lever E^{15} is provided with an outwardly extending arm E^{17} pivotally connected by a link E^{18} with a lever E^{19} (see Fig. 2) fulcrumed on the main frame A, and carrying a friction roller E^{20} 35 traveling in a cam groove of a cam E^{21} secured on the cam shaft Q^3 . Thus when the loom is running and the cam shaft Q^3 and the cam E^{21} are turning, then a periodic up and down swinging motion is given to 40 the lever E^{19} which by the link E^{18} , the arm E^{17} , the bell crank levers E^{15} , the link E^{16} and the links E^{14} causes an up and down sliding motion of the heads E^2 to raise and 45 lower the lower shogging comb E' , that is, to move the same up toward the upper shogging comb E or away from the same, as hereinafter more fully described. 50
- The lay F.*—The lay F is of the usual construction, and its shaft F' is journaled in suitable bearings on the main frame A (see Figs. 8, 9, 10 and 26) and from the said shaft F' depends an arm F^2 pivotally connected by a link F^3 with a lever F^4 fulcrumed on the main frame A. On the lever F^4 is journaled 55 a friction roller F^5 in peripheral engagement with a cam F^6 secured on the cam shaft Q^3 , so that when the loom is running and the shaft Q^3 and the cam F^6 are rotated, then a periodic swinging motion is given to the 60 lever F^4 which by the link F^3 and the arm F^2 rocks the shaft F' so as to swing the lay F forward and backward, as hereinafter more fully described. 65
- In order to hold the friction roller F^5 in firm contact with the peripheral surface of the cam F^6 so as to follow the contour of the cam, heavy springs F^7 are employed attached at one end to the link F^3 and at the other end to the main frame A (see Figs. 8 and 9). 70
- In order to limit the rearward swinging motion of the lay F, a stop screw F^8 is provided mounted on a bracket F^9 attached to the main frame A, the said stop screw F^8 being in alignment with the lower end of the arm F^2 . The dents F^{10} and F^{11} of the lay F are alternately long and short, as plainly shown in Figs. 26 and 40-57; that is, the short dents F^{11} terminate a distance from the top cross-bar of the lay, while the long dents F^{10} extend from the bottom bar to the top bar of the lay. By the arrangement described the ground warp threads a , a' can be crossed and uncrossed above the short dents F^{11} . 75
- The breast beam G.*—The breast beam G (see Figs. 35 and 36) is secured to the frame A and is provided near its sides with two temples G^2 extending in apertures G^3 formed in the breast beam G. The temples G^2 are in the form of spiked rollers journaled in the breast beam G and having their spikes projecting beyond the under surface of the breast beam G to readily enter the cloth f at or near the selvage and while the cloth is drawn along the under surface of the breast beam G by the action of the cloth beam H'. The temples are disposed obliquely relative one to the other, as plainly shown in Fig. 36, so that the temples have the tendency to draw the cloth f outward at both sides, thus holding the cloth properly stretched from one side to the other to allow proper beating in of the pile threads c and the weft threads d , d' , e , e' . The roller G' over which passes the cloth f after leaving the breast beam G holds the cloth f up against the under side of the breast beam G, and this roller is plain and journaled in the sides of the main frame A. 85
- The cloth beam H and take-up mechanism.*—The cloth beam H has its shaft H^2 journaled in suitable bearings on the front end of the main frame A (see Figs. 1, 2, 15, 15^A and 38) and on the left end of the said shaft H^2 is secured a gear wheel H^3 in mesh with a pinion H^4 secured on a short shaft H^5 journaled in the left side of the main frame A, and on the shaft H^5 is secured a ratchet wheel H^6 engaged by pull pawls H^7 , H^8 fulcrumed on an arm H^9 secured on a short shaft H^{10} journaled on the main frame A. On the short shaft H^{10} is secured an arm H^{11} carrying a friction roller H^{12} engaged by three canis H^{13} rotating with the cam shaft Q^3 , so as to impart a periodic swinging motion to the arm H^{11} to rock the shaft H^{10} so that the arm H^9 actuates the pawls H^7 , H^8 to turn the ratchet wheel H^6 which by the gearing described 95

- transversely and journaled in suitable bearings on the main frame A. The endless carrier chains K² also pass over other sprocket wheels (not shown) arranged over head, and common in Axminster and similar looms, so that further description of the same is not deemed necessary, it being, however, understood that when a frame K' and its set of tuft yarn tubes K is carried by
- 5 10 and 26). Near the right hand end of the shaft K¹² is secured a notched locking disk K²⁸ engaged by a lever K²⁷ fulcrumed on the main frame A and pressed on by a spring K²⁸ so as to hold the lever K²⁷ in engagement with one of the notches of the disk K²⁸, to lock the disk and consequently the shaft K¹² against rotation for the time being.
- 10 15 The lever K²⁷ is connected by a link K²⁹ with a lever K³⁰ fulcrumed on the main frame A and provided with a lug K³¹ adapted to be engaged by a cam K³² secured on the cam shaft Q³, so that when the loom is in motion and the cam shaft Q³ and the cam K³² are rotated then the lever K³⁰ receives an intermittent swinging motion, whereby the link K²¹ imparts a swinging motion to the lever K²⁷ so as to disengage the same from the notch in the disk K²⁸ immediately previous to the cam K²⁴ imparting a swinging motion to the lever K²² to turn the shaft K¹², as before explained. The cam K³² allows the lever K³⁰ to immediately return to its former position, that is, as soon as the next notch in the disk K²⁸ is engaged by the lever K²⁷ pressed on by the spring K²⁸. A brake K³³ (see Figs. 1, 5 and 26) is held on the shaft K¹² to prevent the shaft K¹² from gaining too much momentum when intermittently turned, thus allowing proper locking of the shaft K¹² by the lever K²⁷ engaging a notch in the disk K²⁸.
- 15 20 25 30 35 40 45 50 55 60 65 70 75 80 85 90 95 100 105 110 115 120 125 130 The actuating mechanism L.—The actuating mechanism L (see Figs. 1, 10 and 26-34) is used to disengage the frame K' and its tuft yarn tubes K from the endless carrier chains K², to manipulate the frame K' and its tuft yarn tubes K during the formation of the Persian knot, and to return the said frame K' and its tuft yarn tubes K to the endless carrier chains K². For the purpose mentioned the frames K' are adapted to be engaged by sockets L² formed on the lower ends of arms L³—L³ secured on the polygonal bars or shafts L⁴, L⁵ mounted to slide transversely in slides L⁶, L⁷, mounted to slide longitudinally in slides L⁸, L⁹, adapted to move up and down in guideways A¹¹, A¹² secured to or forming part of the main frame A (see Fig. 26).
- In order to impart a transverse sliding movement to the bars L⁴, L⁵ the following device is provided: Each of the bars L⁴, L⁵ (see Fig. 34) is pressed in an inward direction by a spring L¹⁰, so as to move the upper end of each arm L³ in engagement with the spring hook K⁸, to disengage the same from the inner link of the pair of links K⁹ of the endless carrier chains K², as plainly indicated in Fig. 29, to release the frame K' from the endless carrier chains, thus allowing a downward movement of the frame K' with the arms L³ supporting the
- In order to positively lock the shaft K¹² against rotation during the time the frame K' and its set of yarn tubes K are removed, used and returned, the following arrangement is made (see more particularly Figs. 1,

frame by its sockets L^2 . When the frame K is returned to the endless carrier chains then the bars L^4 , L^5 are moved outward against the tension of the springs L^{10} to 5 allow the spring hooks K^8 to reengage the innermost link of the pair of links K^9 so as to re-attach the frame K' to the endless carrier chains K^2 .

For the purpose mentioned the outer ends 10 of the bars L^4 , L^5 are provided with adjustable heads L^{11} , L^{12} (see Figs. 26 and 34) engaged by shifting forks L^{13} , L^{14} fulcrumed on the main frame A and pivotally connected on the main frame A and pivotally connected by links L^{15} , L^{16} with arms L^{17} , L^{18} secured 15 on longitudinally extending shafts L^{19} , L^{20} journaled on the main frame A . The shaft L^{20} (see Fig. 26) is provided with an arm L^{21} connected by a link L^{22} with an arm L^{23} (see Fig. 33) secured on the shaft L^{19} , so 20 that when the latter is rocked a corresponding rocking motion is given to the shaft L^{20} but in an opposite direction and consequently both shifting forks L^{13} and L^{14} are moved in unison toward or away from each 25 other on rocking the shaft L^{19} . On the latter is secured an arm L^{24} pivotally connected by a link L^{25} (see Fig. 7) pressed in an upward direction by a spring L^{26} and pivotally connected at its lower end with a 30 lever L^{27} fulcrumed on the main frame A , and carrying a friction roller L^{28} in peripheral contact with a cam L^{29} secured on the cam shaft Q^3 . Thus when the loom is running and the cam shaft Q^3 and the cam L^{29} 35 are rotated, then a swinging motion is given to the lever L^{27} which by the link L^{25} rocks the shaft L^{19} , and as the latter is connected with the shaft L^{20} and both shafts L^{19} and L^{20} are connected with the shifting forks 40 L^{13} , L^{14} , it is evident that both bars L^4 , L^5 are moved simultaneously outward to disengage the inner ends of the arms L^3 from the spring hooks K^8 to allow the same to re-engage the inner links of the pair of links 45 K^9 of the endless carrier chains K^2 .

Each of the slides L^6 and L^7 is pivotally connected by a link L^{30} with an arm L^{31} and the two arms L^{31} are secured on a transversely extending shaft L^{32} journaled in 50 suitable bearings on the main frame A , (see Figs. 2, 7, 10, 26 and 36). On the shaft L^{32} is secured a rearwardly extending arm L^{33} pressed on by a spring L^{34} and on the said shaft is also secured an arm L^{35} carrying a friction roller L^{36} engaging the peripheral surface of a cam L^{37} secured on the cam shaft Q^3 , so that when the loom is running and the cam shaft Q^3 and the cam L^{37} are 55 rotating then an intermittent rocking motion is given to the shaft L^{32} by the action of the cam L^{37} on the friction roller L^{36} held on the arm L^{35} . Now when the shaft L^{32} is rocked as described, its arms L^{31} and the links L^{30} impart a longitudinal sliding motion 60 to the slides L^6 and L^7 , to carry the

frame K' and its set of tuft yarn tubes K in a longitudinal direction, as hereinafter more fully described.

In order to impart an intermittent up and down sliding motion to the slides L^8 and L^9 , the following device is provided: Each of the slides L^8 and L^9 is pivotally connected by an upwardly extending link L^{38} with an arm L^{39} , and the two arms L^{39} are secured on the shaft L' previously mentioned, and the said shaft L' is provided with an arm L^{40} (see more particularly Figs. 10 and 39) pivotally connected by a link L^{41} with a lever L^{42} fulcrumed at L^{43} on the main frame A . On the lever L^{42} is journaled a friction roller L^{44} traveling in a cam groove on a cam L^{45} secured on the cam shaft Q^3 , so that when the loom is in motion and the shaft Q^3 and the cam L^{45} are rotating then an intermittent up and down swinging motion is given to the lever L^{42} which by the link L^{41} and the arm L^{40} rocks the shaft L' to cause the arms L^{39} to swing up and down, and by the links L^{38} intermittently cause the slides L^8 and L^9 to move 80 up and down on their guideways A^{11} and A^{12} .

The needles N and N' .—The needles N and N' extend transversely one above the other and are secured at their right-hand ends in a cross head N^2 mounted to slide transversely on guideways A^{15} arranged on the main frame A . The needles N , N' are of lengths somewhat in excess of the width of the fabric f , to extend clear through the open sheds from one side of the fabric to the other when carrying the weft threads d^2 and e^2 through the open sheds, as hereinafter more fully described.

During the formation of a row of Persian knots the needles N , N' are at rest in a withdrawn position on the right side of the loom (see Figs. 1 and 12). In order to intermittently reciprocate the needles N , N' , the following device is provided, special reference being had to Figs. 1, 11, 12 and 14: The cross head N^2 is pivotally connected by a link N^3 with the upper end of a lever N^4 mounted to swing loosely on a shaft P' extending longitudinally and journaled in suitable bearings on the main frame A , the shaft P' forming part of the pile thread cutting mechanism. The lever N^4 is pivotally connected by a link N^5 with a bell crank lever N^6 connected by a link N^7 with a longitudinally extending lever N^8 fulcrumed on the main frame A , as plainly indicated in Fig. 14. On the lever N^8 is journaled a friction roller N^9 traveling on the peripheral face of a cam N^{10} secured on the cam shaft Q^3 , and the inner face of the rim of the cam N^{10} is engaged by a friction roller N^{11} journaled on a lever N^{12} fulcrumed on a bracket N^{13} of the lever N^8 , and the said lever N^{12} is pressed on by a cushion spring N^{14} held on the lever 100 110 115 120 124 130

N⁸. The friction rollers N⁹, N¹¹ are disposed opposite each other on the outer and inner faces of the rim of the cam N¹⁰, so that when the cam shaft Q³ is running and the cam N¹⁰ is turned then an up and down swinging motion is given to the lever N⁸ by the action of the friction rollers N⁹ and N¹¹.

The motion of the lever N⁸ is transmitted by the link N⁷ to the bell crank lever N⁶ 10 which by the link N⁵, the lever N⁴ and the link N³, imparts a transverse sliding motion to the cross head N² so as to move the needles N, N' transversely through the open sheds and back again to their position of rest on 15 the right side of the machine, as hereinafter more fully explained. Now by having the friction roller N¹¹ cushioned as described, it is evident that the needles N, N' in going through the open sheds can readily yield in 20 case of an obstruction in the open sheds, it being understood that the movement of the needles from the right to the left is caused by the action of the friction roller N¹¹ on the cam N¹⁰, and the return movement of the 25 needles is caused by the action of the friction roller N⁹ on the cam N¹⁰.

The weft threads d², e² unwind from spools N¹⁵ (see Fig. 11) held on the main frame A, and the said threads then pass 30 through a tension device R and finally through the eyes of the needles N, N'. The tension device R is mounted on a frame R' (see more particularly Figs. 11 and 14) attached to the main frame A, and on the 35 frame R' is secured a tension block R² operating in conjunction with a tension lever R³ for clamping the threads d², e², the clamping lever R³ being fulcrumed on the frame R' and pressed on by a spring R⁴ so 40 as to give the desired tension to the two threads passing between the block R² and the lever R³. The threads after leaving the block R² and the lever R³ pass up through an eye R⁵ held on the upper end of the frame R', and the threads then pass around the front side of an arm R⁶ secured on a short shaft R⁷ and pressed on by a weight R⁸ so 45 as to normally hold the arm R⁶ against the eye R⁵, as shown in Figs. 11 and 14. On the short shaft R⁷ is secured an arm R⁹ connected by a link R¹⁰ with a lever R¹¹ fulcrumed on the main frame A and adapted to be engaged by a cam R¹² secured on the cam shaft Q³, so that when the loom is running 50 and the cam shaft Q³ and the cam R¹² are rotated then an intermittent swinging motion is given to the lever R¹¹, which by the link R¹⁰ and the arm R⁹ rocks the shaft R⁷ so as to swing the arm R⁶ toward the front to take 55 up the weft threads d², e² with a view to hold the same taut in the needles N, N'.

The selvage-forming device O.—The needles N, N' operate in conjunction with the selvage-forming device O (see Figs. 15 60 to 21) to form a selvage on the left side of

the fabric f, the selvage on the right side of the fabric being formed on changing the sheds after the needles are withdrawn and previous to their next movement through the open sheds. The weft threads d², e² 70 operate in conjunction with a looping thread g to form the selvage, and this looping thread g unwinds from the spools O' held on a shuttle O² mounted to slide up and down in a guideway O³ attached to or forming part of the bracket A³. The shuttle O² is provided with a rack O⁴ in mesh with gear wheels O⁵, O⁶ journaled on the bracket A³, as plainly indicated in Fig. 19. The rack O⁴ is connected with the ends of two ropes O⁸, O⁹ extending in opposite directions and passing over pulleys O¹⁰, O¹¹ journaled on the bracket A³, the ropes O⁸, O⁹ then extending rearwardly and connecting with a lever O¹² (see Fig. 15) fulcrumed at 80 its middle on the main frame A and provided with an arm O¹³ connected by a link O¹⁴ with a lever O¹⁵ fulcrumed on the main frame A and pressed on by a spring O¹⁶. The lever O¹⁵ is provided with a stop screw O¹⁷ adapted to abut on the main frame A to limit the swinging motion of the lever O¹⁵. On the latter is journaled a friction roller O¹⁸ traveling on the peripheral face of a cam O¹⁹ secured on the cam shaft Q³, so that 85 when the latter is rotated the cam O¹⁹ imparts a periodic swinging motion to the lever O¹⁵ which by the link O¹⁴ rocks the lever O¹², so that the ropes O⁸, O⁹ cause the rack O⁴ to slide up or down, whereby the gear wheels O⁵, O⁶ are turned to move the shuttle O² down or up, that is, in a reverse direction to the movement given to the rack O⁷.

By the arrangement described the looping thread g is carried from the left side of the fabric either up above the same or down below the fabric, to be engaged by the needles N, N' and their weft threads d², e² (see Fig. 17) with a view to loop each thread around the looping thread g, thus holding the loops of each thread d², e² on the left hand side of the fabric during the time the needles N, N' return and consequently the double weft threads d d', d' d', e e, and e' e' are held in each open shed during two successive picks, as hereinafter more fully described. The looping thread g after unwinding from its spool O' passes through a tension device O²⁰ held on the shuttle O² (see Figs. 20 and 21) and serving to keep the looping thread g under proper tension; that is, to prevent the weft threads d², e² from drawing the looping thread through the open sheds on the withdrawal or return movement of the needles N, N'. 110

The pile thread cutter P.—The cutter P (see Figs. 1, 11, 12, 13, 14, 17 and 19) is in the form of a shearing knife secured to a head P² attached to a cross head P³ mounted to slide transversely on a guideway A¹⁵ 120 125 130

forming part of the main frame A. The cross head P³ is connected at its outer end by a link P⁴ with an arm P⁵ secured on the shaft P' previously mentioned, and on the 5 said shaft is secured an arm P⁶ connected by a link P⁷ with a lever P⁸ fulcrumed on the main frame A and carrying a friction roller P⁹ (see Figs. 11 and 12) traveling in a cam groove of a cam P¹⁰ secured on the 10 cam shaft Q³. Thus when the loom is running and the cam shaft Q³ and the cam P¹⁰ are rotating then an intermittent swinging motion is imparted to the lever P⁸, which by 15 the link P⁷, arm P⁶, shaft P', arm P⁵ and link P⁴ causes the cross head P³ to reciprocate transversely so that the cutter P cuts the pile thread c with a shear cut below the fabric f, as hereinafter more fully described.

Hand power.—It is sometimes necessary 20 for the weaver to rotate the cam shaft Q³ by hand instead of driving it by power from the main shaft Q. For this purpose the following arrangement is made, special reference being had to Figs. 1, 11, 12, 14 and 36. 25 A hand wheel S is secured on the upper end of a shaft S' journaled at its upper end in a bearing S² secured to the main shaft A, and the lower end of the said shaft S' is stepped in an arm S³ fulcrumed at S⁴ on the main 30 frame A. A spring S⁵ is connected with the arm S³ for holding the latter normally in an uppermost position, the upward movement of the arm S³ and consequently that of the shaft S' being limited by a stop collar S⁶ secured on the shaft S' and adapted to abut against the bearing S². On the lower 35 end of the shaft S' is secured a bevel pinion S⁷ in mesh with a bevel gear wheel S⁸ secured on a short transversely extending shaft S⁹ journaled in suitable bearings on the arm S³. On the shaft S⁹ is secured a spur wheel S¹⁰ normally out of mesh with the gear wheel Q⁸ but adapted to be moved into mesh with the said gear wheel on swinging the 40 arm S³ downward. For this purpose the arm S³ is pivotally connected by a link S¹¹ with a treadle S¹² fulcrumed on the main frame A, and under the control of the weaver's foot, so that when the weaver 45 presses the treadle S downward then the link S¹¹ imparts a downward swinging motion to the arm S³ so as to move the pinion S¹⁰ in mesh with the gear wheel Q⁸. Now when 50 this takes place and the operator turns the hand wheel S then a rotary motion is given to the shaft S' which by the pinion S⁷ and the gear wheel S⁸ rotates the shaft S⁹ and consequently the pinion S¹⁰ so that the latter turns the gear wheel Q⁸ and consequently 55 the cam shaft Q³. Now in rotating the cam shaft Q³ the several mechanisms of the loom are actuated the same as if the cam shaft Q³ had been turned by power from the main driving shaft Q.

60 When the treadle S¹² is pressed downward

the power gear is automatically thrown out of action, and for this purpose the treadle S¹² is provided with a pin engaging the slotted lower end of a link S¹⁴ connected with an arm S¹⁵ secured on the shaft Q¹⁴, 70 and when the treadle S¹² is pressed, as previously explained, then the link S¹⁴ and arm S¹⁵ turn the shaft Q¹⁴ to throw the clutch mechanism for the main shaft Q out of action. As soon as the operator releases the 75 pressure of the treadle S¹² the spring S⁵ returns the several parts to the normal position, that is, swings the arm S³ upward thus moving the pinion S¹⁰ out of mesh with the gear wheel Q⁸.

80 The operation is as follows: When the loom is running and the several parts are in the position illustrated, notably in Figs. 1, 2, 5, 26 and 40, then the lay F is in a rearmost position after having beaten in the last pair of double weft threads d, e. The ground warp threads a, a' of each pair of ground warp threads are in their normal parallel position (see Fig. 40^A), and a frame K' with a set of tuft yarn tubes K has been detached 90 from the endless carrier chains K² by the actuating mechanism L, which latter now carries the said frame K' and its tuft yarn tubes K downward and manipulates the same for forming a row of Persian knots; 95 that is, each pile thread c is formed into a Persian knot on a corresponding pair of ground warp threads a, a'. The let-off mechanism for the warp beam B, the endless carrier chains K², the take-up mechanism 100 for the cloth beam H, the needles N, N', the selvage-forming device and the pile thread cutter P are now in a position of rest.

By the combined action of the cams L³⁷ and L⁴⁶ the slides L⁶, L⁷ and L⁸, L⁹ are now 105 simultaneously actuated so as to move the tuft yarn tubes K in a sweep downward and rearward in the position shown in Fig. 41, and at the same time the cam E¹⁵ and its connections shift the combs E, E' of the 110 shogging device transversely in opposite directions, to cross the ground warp threads a, a' between the fabric f and the combs E, E', and in the space above the short dents F¹¹ of the lay F, and then the cam F⁶ and 115 its connections with the lay F cause the latter to swing forward to the position shown in Fig. 41 and Fig. 41^A, so that the short dents F¹¹ pass up between the ground warp threads a, a' of each pair of ground warp 120 threads and in the rear of the crossing A² thereof to keep the ground warp threads a, a' in a crossed position in front of the dents F¹⁰, F¹¹ of the lay, as plainly shown in Fig. 41^A. The ground warp threads a, a' 125 are shifted by the shogging combs E, E' in approximately the same horizontal plane so that when the lay F swings forward, as above described, the short dent F¹¹ of the lay F readily passes between the correspond- 130

ing pair of ground warp threads a, a' without danger of missing either of the ground warp threads a, a' . By having the ground warps a, a' practically in the same plane it is possible to use comparatively short tuft yarn tubes. The lay F advances and the tuft yarn tubes K move downward and rearward until the points of the tuft yarn tubes K are close to the front edges of the short dents F^{11} and pass down between the ground warp threads a, a' in the rear of the crossing A^2 , as plainly shown in Figs. 42 and 42^A. The tuft yarn tubes K are now moved straight down to the position shown in Fig. 43, and by the action of the cam L^{45} and its connections, lowering the slides L^8, L^9 only, the other slides L^6 and L^7 now ceasing their rearward movement by the action of the corresponding cam L^{37} and its connections. The lay F at the same time moves rearward to the position shown in Figs. 43 and 43^A, to allow a ready downward movement of the tuft yarn tubes K without danger of the ground warp threads a, a' unduly clamping the tuft yarn tubes. The tuft yarn tubes K now rise straight up by the action of the slides L^8, L^9 and their connections with the cam L^{45} until the points of the tuft yarn tubes are disengaged from the ground warp threads, so that the depending ends of the pile threads c hang downward between the crossed ground warp threads a, a' .

It will be noticed that by the arrangement described the pile threads c hang down straight from the points of the tuft-yarn tubes K and below the ground warp threads a, a' , and hence are not liable to be entangled with the dents F^{19}, F^{11} of the lay F or with the ground warp threads a, a' . The lay F now goes back to allow the ground warp threads a, a' to rise above the upper ends of the dents F^{11} , for the ground warp threads a, a' to pass back into their parallel position by the shogging combs E and E' being moved in a corresponding direction, as plainly indicated in Figs. 44 and 44^A. Now when this takes place the half knot is formed and the lay F now swings forward to the position shown in Figs. 45 and 45^A, and then both the tuft yarn tubes K and the lay F move together forward so as to beat up the pile thread c , the pointed ends of the tubes K being close to the front ends of the dents of the lay F during the simultaneous forward movement of the tuft yarn tubes K and the lay F.

As the ground warp threads a, a' are uncrossed shortly after the tuft yarn tubes K have risen above the ground warp threads a, a' and previous to the lay F starting to beat up the half knot formed, it is possible to beat up the half knot very firmly and without danger of the pile threads c becoming entangled in the dents of the lay F, es-

pecially as the ground warps a, a' are now uncrossed or parallel, and the dents F^{11} engage the pile threads c while the latter extend transversely between the ground warps a, a' , as will be understood by reference to Fig. 45^A. By thus beating up the half knot firmly, it is not liable to slip during the subsequent completion of the loop and the cutting of the pile threads.

When the lay F and the tuft yarn tubes K have reached the beaten up position shown in Fig. 46, then the tuft yarn tubes K rise straight up to the position shown in dotted lines in Fig. 46, and at the same time the lower comb E' is moved downward by the action of the cam E²¹ and its connections, and the heddles C and C' are moved to an approximately central position by the action of the cams C¹⁴, C¹⁵ and their connections, so that the several parts assume the position shown in Fig. 46. The let-off mechanism for the warp beam B and the take-up mechanism for the cloth beam H are at about this time actuated to wind up the fabric f and to unwind the ground warp threads a, a' .

The tuft yarn tubes K when moving into the upward position just described and shown in dotted lines in Fig. 46, unwind a sufficient amount of the pile threads c from the spool K⁵ so that after the pile thread is cut a portion still depends from the tuft yarn tubes K, for forming another Persian knot, when this set of tuft yarn tubes K is subsequently carried around again by the endless chains K² to active position in the actuating mechanism L, as above described. The lay F now swings a short distance backward (see Fig. 47) without, however, raising the ground warp threads a, a' above the short dents F^{11} , and at the same time the tuft yarn tubes K are caused to move downward and rearward by the combined action of the slides L^6, L^7 and L^8, L^9 and their cams and connections, as previously explained. By this movement of the tuft yarn tubes K their points pass between the ground warp threads a, a' close to the front edges of the short dents F^{11} , and then the tuft yarn tubes K are moved straight downward while the lay F recedes still farther until the parts have assumed the position shown in Fig. 48. When this takes place the cam P¹⁰ and its connections cause the cutter P to move transversely so as to cut the pile threads c at a point between the bottom of the fabric and the points of the tuft yarn tubes, as will be readily understood by reference to Fig. 48.

It is understood that when the tuft yarn tubes K pass down between the ground warp threads a, a' the second time and the pile threads c are cut by the cutter P, as shown in Fig. 48, the Persian knot is completed. When this has been done the cutter P re-

means for the time being at the left side of the machine, but the tuft yarn tubes K now rise straight up to the position shown in dotted lines in Fig. 49 and then move straight forward to the position shown in full lines in Fig. 49, and at the same time the lay F swings forward to beat in the row of Persian knots formed on the ground warp threads a, a' . The tuft yarn tubes K are now carried straight up by the action of the slides L^3, L^2 , to return the tuft yarn tubes with their frame K' to the endless carrier chains K², after which an intermittent rotary motion is given to the shaft K¹² by the action of the cam K²¹ and its connections with the cam shaft K¹², so that another set of tuft yarn tubes is moved into a lowermost or withdrawing position. The heddles C, C' and the yarn tubes J, J' now change position, that is, the heddle C' and the yarn tubes J move up while the heddle C and the yarn tubes J' move downward to the position illustrated in Fig. 50, so as to open the two sheds one above the other, that is, one between the ground warp threads a, b and the other between the ground warp threads a', b' .

The lay F is held firmly up against the beaten up row of Persian knots during the change of the heddles C, C' and the yarn tubes J, J', so that a possible loosening of the Persian knots is prevented during the up and down movement given to the ground warp threads a, a' and the reinforcing warp threads b, b' by the heddles C, C' and the yarn tubes J, J' respectively. The lay F now swings back to the position shown in Fig. 51, and then the cam N¹⁰ and its connection with the needles N, N' cause the latter to move transversely through the open sheds mentioned, the eyes of the needles N, N' now passing beyond the shuttle O² (see Figs. 16 and 17), and when this takes place the shuttle O² rises above the needles N, N', to carry the looping thread g up between the threads d², e² by the needles N, N', and then the latter return back through the open sheds to their normal position of rest at the right side of the machine. Now when this takes place the looping thread g retains the threads d², e² in loops at the left ends so that the double weft threads d', e' are held in the open sheds from one side of the fabric to the other (see Fig. 51), and then the lay F swings forward to beat in the said double weft threads d', e' as indicated in Fig. 52. The let-off mechanism for the warp beam B and the take-up mechanism for the cloth beam H are at about this time actuated to wind up the fabric f and to unwind the ground warp threads a, a' .

After the weft threads d', e' are beaten up,

the heddles C, C' and the yarn tubes J, J' change position, that is, they move to an approximately middle position, as indicated in Fig. 53, and then move to the open position shown in Fig. 54; that is, the heddle C and the yarn tubes J' move into an uppermost position, while the heddle C' and the yarn tubes J move into a lowermost position, as indicated in Fig. 54. By this movement the ground warp threads a, a', b, b' are crossed in an up and down direction, so as to form two open sheds, one between the ground warp thread a and the reinforcing warp thread b , and the other between the ground warp thread a and the reinforcing warp thread b' . The lay F now swings rearward and the knife P goes back to its position of rest. The needles N, N' again move through the open sheds (see Fig. 55) and the threads d, e are again interlooped with the looping thread g by the shuttle O² now moving downward. The needles N, N' now immediately return to their position of rest on the right side of the machine thus leaving the second double weft threads d and e in the open sheds.

During the two return movements of the needles N, N' described, the tension arm R is swung forward by the action of the cam R¹² and connections, so as to draw the threads d, e taut on the looping thread g to form a proper selvage on the left side of the fabric. As previously stated the selvage on the right side of the fabric is formed by the change of the ground warp threads a, a' and b, b' between the second and third picks and previous to the passage of the needles N, N' through the open sheds. The lay F now swings forward and thus beats up the double weft threads d, e. The let-off mechanism for the warp beam B and the take-up mechanism for the cloth beam H both previously described are at about this time actuated to wind up the fabric f and to unwind the ground warp threads a, a' . At about this time the actuating mechanism L has engaged the second set of tuft yarn tubes K and removes the same from the carrier chains K² and moves the same downward to operative position, as indicated in Fig. 55.

When the lay F reaches the final beating in position, as indicated in Fig. 56, then the new set of tuft yarn tubes K is adjacent to the front of the lay at the upper end thereof, and then the new set of yarn tubes move straight downward to the position shown in Fig. 40, at the same time the heddles C, C' and the yarn tubes J, J' move to the position indicated in Fig. 57; that is, both sides of the yarn tubes J, J' are now elevated and the heddle C has risen sufficiently to engage the ground warp thread a with the teeth of the comb E, and then the lay F swings

backward to the position shown in Fig. 40, so that both ground warp threads a and a' rise above the dents F^{11} , and then the comb E' is raised to engage the ground warp thread a' , after which the combs E and E' are shifted transversely to again cross the ground warp threads a and a' previous to the lay F swinging forward to the position shown in Fig. 41^A. The above described operation is then repeated.

From the foregoing it will be seen that for every three picks the cam shaft Q^3 makes one revolution and the operation repeats itself after each third pick, but the successive rows of pile threads c are different in color, to conform to the predetermined design to be given to the pile face of the fabric.

It will be noted that during the formation of a row of Persian knots, each tuft yarn tube K passes down twice between the ground warps a, a' ; that is, first when the said ground warps a, a' are crossed and then when they are uncrossed or in their normal parallel position. In order to insure an accurate formation of the Persian knots on the several pairs of ground warp threads a, a' , each tuft yarn tube K enters its pair of ground warp threads a, a' close to the lay F especially when the ground warp

threads a, a' are crossed, as then the ground warp threads a, a' are farthest apart on opposite sides of the corresponding dents F^{11} and hence the tuft yarn tube K is not liable to pass down outside either of the ground warp threads a or a' . It has been found of advantage to move the tuft yarn tubes K in unison with the lay F (see Fig. 42), to prevent binding of the yarn tubes K by the ground warp threads a, a', b, b' .

It is understood that when the tuft yarn tubes are inserted between the crossed ground warp threads a, a' and move forward and finally out of the ground warp threads a, a' , then the depending end of the pile thread c is firmly clamped between the ground warp threads a, a' as soon as the latter return to normal parallel position (see Fig. 45^A), and hence when the tuft yarn tubes K are subsequently passed the second time between the parallel uncrossed ground warp threads a, a' , then the clamped portion of the pile thread c is not liable to slip or become disconnected from the ground warp threads a, a' , especially during the subsequent shearing action by the cutter P (see Fig. 48).

The reinforcing ground warp threads b, b' pass through the lay F and move approximately up and down in unison with the ground warp threads a, a' although the movement given to the yarn tubes J, J' carrying the said reinforcing ground warp threads b, b' is wholly independent of the movement given to the heddles C, C' carry-

ing the ground warp threads a, a' . By the arrangement described, the weft threads d, d' and the reinforcing weft threads e, e' are interwoven with the ground warp threads a, a' and b, b' in the manner described, so that an exceedingly strong and durable fabric with a reinforced back is produced and at the same time the pile threads c are securely bound in place to prevent the same from becoming loose when the fabric is in use.

On omitting the reinforcing warp threads b, b' and the upper needle N' and its weft thread e , it is possible to weave a plain pile fabric having Persian knots but without being reinforced.

Having thus described my invention, I claim as new and desire to secure by Letters Patent:

1. A pile fabric loom comprising a lay, means for intermittently actuating the said lay, a shogging device for crossing and uncrossing the ground warp threads, a tuft yarn tube carrying the pile thread, and means for moving the said yarn tube twice between the said ground warp threads and relative to the movement given to the lay and the shogging device to form a Persian knot.

2. A pile fabric loom comprising a lay, means for intermittently actuating said lay, a pair of heddles for the ground warp threads, a fixed reed for the passage of the ground warp threads, a shogging device for crossing and uncrossing the ground warp threads, a tuft yarn tube, and means for moving the said tuft yarn tube twice between the said ground warp threads and relative to the movement given to the lay and the rocking device.

3. A pile fabric loom, comprising a lay, means for intermittently actuating the said lay, a pair of heddles for the ground warp threads, a fixed reed for the passage of the ground warp threads and arranged in front of the heddles, a shogging device interposed between the said reed and the said lay for crossing and uncrossing the ground warp threads, tuft yarn tubes carrying the pile threads, and means for moving the said tuft yarn tubes twice between the said ground warp threads and relative to the movement given to the said lay and the said shogging device to form Persian knots on the said ground warp threads.

4. A pile fabric loom comprising a lay, means for intermittently actuating the said lay, a pair of heddles for the ground warp threads, a fixed reed for the passage of the ground warp threads and arranged in front of the heddles, a shogging device interposed between the said reed and the said lay, tuft yarn tubes carrying the pile threads, means for operating the said tuft yarn tubes in

conjunction with the said lay and the said shogging device to form Persian knots on the said ground warp threads, yarn tubes carrying reinforcing warp threads, and means for actuating the same in unison with the said heddles.

5. A pile fabric loom comprising a lay, means for intermittently actuating the said lay, a pair of heddles for the ground warp threads, a fixed reed for the passage of the ground warp threads and arranged in front of the heddles, a shogging device interposed between the said reed and the said lay, tuft yarn tubes carrying the pile threads, means 10 for operating the said tuft yarn tubes in conjunction with the said lay and the said shogging device to form Persian knots on the said ground warp threads, and yarn tubes carrying reinforcing warp threads and arranged between the said lay and the said shogging device.

6. A pile fabric loom comprising a lay, means for intermittently actuating the said lay, a pair of heddles for the ground warp threads, a fixed reed for the passage of the ground warp threads and arranged in front of the heddles, a shogging device interposed between the said reed and the said lay, tuft yarn tubes carrying the pile threads, means 25 for operating the said tuft yarn tubes in conjunction with the said lay and the said shogging device to form Persian knots on the said ground warp threads, and yarn tubes carrying reinforcing warp threads and arranged between the said lay and the said shogging device, and means for actuating the same in unison with the said heddles.

7. A pile fabric loom, comprising a lay, 40 heddles, a shogging device, tuft yarn tubes carrying the pile threads to be formed into Persian knots on the ground warp threads, means for passing the tuft yarn tubes twice between the ground warp threads and relative to the movement given to the lay and the shogging device, means for introducing reinforcing warp threads, and means for introducing two wefts, one for binding the ground warp threads, and the other for 45 binding the reinforcing warp threads.

8. A pile fabric loom comprising a lay, means for intermittently actuating the said lay, a pair of heddles for the ground warp threads, a fixed reed for the passage of the 50 ground warp threads and arranged in front of the heddles, a shogging device interposed between the said reed and the said lay, tuft yarn tubes carrying the pile threads, means for operating the said tuft yarn tubes in conjunction with the said lay and the said shogging device to form Persian knots on the said ground warp threads, and yarn tubes carrying reinforcing warp threads, means 55 for actuating the same in unison with the

said heddles, and means for introducing two 60 wefts simultaneously, one weft for binding the ground warp threads and the other for binding the reinforcing warp threads.

9. A pile fabric loom comprising a lay, means for intermittently actuating the said lay, a pair of heddles for the ground warp threads, a fixed reed for the passage of the ground warp threads and arranged in front of the heddles, a shogging device interposed between the said reed and the said lay, tuft 70 yarn tubes carrying the pile threads, means for operating the said tuft yarn tubes in conjunction with the said lay and the said shogging device to form Persian knots on the said ground warp threads, and yarn tubes 75 carrying reinforcing warp threads, means for actuating the same in unison with the said heddles, and means for simultaneously introducing two double wefts, one double weft for binding the ground warp threads 80 and the other for binding the reinforcing warp threads.

10. A pile fabric loom comprising a lay, heddles for the ground warp threads, a shogging device for the ground warp 90 threads, tuft yarn tubes, means for moving the said tuft yarn tubes twice between the ground warp threads and relative to the movement given by the said lay and the said shogging device for forming knots on 95 the said ground warp threads, and yarn tubes for introducing reinforcing warp threads, and means for simultaneously introducing two wefts, one for binding the said ground warp threads and the other for binding the said 100 reinforcing warp threads.

11. A pile fabric loom comprising a lay, heddles for the ground warp threads, a shogging device for the ground warp threads, tuft yarn tubes, means for moving 105 the said tuft yarn tubes twice between the ground warp threads and relative to the movement given to the said lay and the said shogging device for forming knots on the said ground warp threads, and yarn tubes for 110 introducing reinforcing warp threads, means for operating the said yarn tubes in unison with the heddles, and means for simultaneously introducing two double wefts, one for binding the said ground warp threads 115 and the other for binding the said reinforcing warp threads.

12. A pile fabric loom comprising a lay, heddles for the ground warp threads, a shogging device for the ground warp 120 threads, tuft yarn tubes, means for moving the said tuft yarn tubes twice between the ground warp threads and relative to the movement given to the said lay and the said shogging device for forming knots on the 125 said ground warp threads, and yarn tubes for introducing reinforcing warp threads, and means for successively introducing a plu-

rality of sets of weft threads, each set of weft threads having two weft threads, one for binding the ground warp threads and the other for binding the reinforcing warp threads.

13. A pile fabric loom comprising a lay, heddles for the ground warp threads, a shogging device for the ground warp threads, tuft yarn tubes, means for moving the said tuft yarn tubes twice between the ground warp threads and relative to the movement given to the said lay and the said shogging device for forming knots on the said ground warp threads, yarn tubes for introducing reinforcing warp threads, and means for successively introducing a plurality of sets of weft threads, each set of weft threads being formed of two double weft threads, one for binding the ground warp threads and the other for binding the reinforcing warp threads.

14. A pile fabric loom comprising a lay having alternate long and short dents for the passage of a pair of ground warp threads between successive long dents, to allow the ground warp thread of the pair of ground warp threads to cross and uncross above the short dents and to allow either ground warp thread to pass from one side of the short dent to the other side thereof, means for intermittently reciprocating the said lay, a shogging device for the said ground warp threads to cross and uncross the same, heddles for raising and lowering the said ground warp threads, a set of tuft yarn tubes carrying the pile threads, and means for intermittently actuating the said set of tuft yarn tubes relative to the movement of the lay and the shogging device, and in the sequence described to form Persian knots on the said ground warp threads.

15. A pile fabric loom comprising a lay having alternate long and short dents for the passage of a pair of ground warp threads between successive long dents, to allow the ground warp threads of the pair of ground warp threads to cross and uncross above the short dents and to allow either ground warp thread to pass from one side of the short dent to the other side thereof, means for intermittently reciprocating the said lay, a shogging device for the said ground warp threads to cross and uncross the same, heddles for raising and lowering the said ground warp threads, a set of tuft yarn tubes carrying the pile threads, means for intermittently actuating the said set of tuft yarn tubes relative to the movement of the lay and the shogging device, and in the sequence described to form Persian knots on the said ground warp threads, and a cutter for shearing the pile threads at the time the latter are held taut between the fabric body and the tuft yarn tubes.

16. A pile fabric loom comprising a lay having alternate long and short dents for the passage of a pair of ground warp threads between successive long dents to allow the ground warp threads of the pair of ground warp threads to cross and uncross above the short dents and to allow either ground warp thread to pass from one side of the short dent to the other side thereof, means for intermittently reciprocating the said lay, a shogging device for the said ground warp threads to cross and uncross the same, heddles for raising and lowering the said ground warp threads, a set of tuft yarn tubes carrying the pile threads, means for intermittently actuating the said set of tuft yarn tubes relative to the movement of the lay and the shogging device, and in the sequence described to form Persian knots on the said ground warp threads, and a transversely moving and angularly disposed knife for cutting the pile threads at a point between the fabric body and the tuft yarn tubes.

17. A pile fabric loom comprising a lay having alternate long and short dents for the passage of a pair of ground warp threads between successive long dents, to allow the ground warp thread of the pair of ground warp threads to cross and uncross above the short dents and to allow either ground warp thread to pass from one side of the short dent to the other side thereof, means for intermittently reciprocating the said lay, a shogging device for the said ground warp threads to cross and uncross the same, heddles for raising and lowering the said ground warp threads, a set of tufted yarn tubes carrying the pile threads, means for intermittently actuating the said set of tufted yarn tubes relative to the movement of the lay and the shogging device, and in the sequence described to form Persian knots on the said ground warp threads, and a transversely reciprocating and angularly disposed knife for cutting the pile threads held inclined and taut by the said tuft yarn tubes.

18. A pile fabric loom comprising means for forming a Persian knot on a pair of ground warp threads, means for introducing reinforcing warp threads one on each side of a Persian knot, and means for introducing two sets of weft threads, so that one set of weft threads is in front of a Persian knot and the other in the rear thereof, each set of weft threads having two weft threads, one for binding the said ground warp threads and the other the reinforcing warp threads.

19. A pile fabric loom for interweaving ground warp threads, weft threads and pile threads provided with means for crossing the ground warp threads, means for passing the pile thread loosely between a pair of

crossed ground warp threads, means for returning the ground warp threads to normal parallel or uncrossed position to clamp the end portion of the pile thread and to pass 5 the end portion around one ground warp thread, means for passing the pile thread between the parallel ground warp threads to loop the pile thread completely around the ground warp thread, and means for cutting 10 the pile thread a distance from the ground warp threads.

20. A pile fabric loom for interweaving ground warp threads, reinforcing warp threads, and set of weft threads, provided 15 with means for crossing a pair of normally parallel ground warp threads, means for passing a pile thread between the crossed ground warp threads, means for returning the crossed ground warp threads to normal 20 parallel position to pass the pile thread over one ground warp thread and under the second ground warp thread, means for passing one end of the pile thread between the ground warp threads while in normal position, to completely loop the pile thread 25 around the second ground warp thread, means for cutting off the pile thread a distance from the second ground warp thread, and means for successively passing sets of 30 weft threads through successively open sheds to bind the ground warp threads and the reinforcing warp threads.

21. A pile fabric loom for interweaving ground warp threads, weft threads, and pile 35 threads provided with an intermittently reciprocating lay, a shogging device for the ground warp threads, tuft yarn tubes carrying the pile threads, means for crossing a pair of normally parallel ground warp 40 threads, with the lay in a rearmost inactive position, means for moving the lay forward to keep the ground warp threads crossed in front of the lay, means for passing the pile thread between the crossed ground warp 45 threads in front of the lay, means for uncrossing the ground warp threads, means for beating up the pile thread by the lay, means for returning the lay, and means for passing the pile thread between the parallel ground 50 warp threads in front of the lay for completing the knot.

22. A pile fabric loom for interweaving ground warp threads, weft threads and pile 55 threads, provided with an intermittently reciprocating lay, a shogging device for the ground warp threads, tuft yarn tubes carrying the pile threads, means for crossing a pair of normally parallel ground warp threads with the lay in a rearmost inactive 60 position, means for moving the lay forward to keep the ground warp threads crossed in front of the lay, means for passing the pile thread between the crossed ground warp threads in front of the lay, means for un-

crossing the ground warp threads, means for 65 beating up the pile thread by the lay, means for returning the lay, means for passing the pile thread between the parallel ground 70 threads in front of the lay for completing the knot, and means for cutting the pile thread between the fabric and the tuft yarn tube while the latter is in a lowermost and rearward position.

23. A pile fabric loom for interweaving ground warp threads, weft threads and pile 75 threads provided with an intermittently reciprocating lay, a shogging device for the ground warp threads, tuft yarn tubes carrying the pile threads, means for crossing a pair of normally parallel ground warp 80 threads with the lay in a rearmost position, means for moving the lay forward to keep the ground warp threads crossed in front of the lay, means for passing the pile thread between the crossed ground warp threads in 85 front of the lay, means for uncrossing the ground warp threads, means for beating up the pile thread by the lay, means for returning the lay, means for passing the pile thread between the parallel ground warp threads in 90 front of the lay for completing the knot, means for cutting the pile thread between the fabric and the tuft yarn tube while the latter is in a lowermost and rearward position, and means for beating up the separated 95 knot.

24. A pile fabric loom for interweaving ground warp threads, weft threads and pile threads, provided with an intermittently reciprocating lay, a shogging device for the 100 ground warp threads, tuft yarn tubes carrying the pile threads, means for crossing a pair of normally parallel ground warp threads with the lay in a rearmost position, means for moving the lay forward to keep 105 the ground warp threads crossed in front of the lay, means for passing the pile thread between the crossed ground warp threads in front of the lay, means for uncrossing the ground warp threads, means for beating up 110 the pile thread by the lay, means for returning the lay, means for passing the pile thread between the parallel ground warp threads in front of the lay for completing the knot, means for cutting the pile thread between 115 the fabric and the tuft yarn tube while the latter is in a lowermost and rearward position, means for beating up the separated knot, and means for introducing successive weft threads to bind the ground warp 120 threads.

25. A pile fabric loom for interweaving ground warp threads, reinforcing warp threads, sets of weft threads and pile threads provided with an intermittently reciprocating lay, a shogging device for the ground warp threads, tuft yarn tubes carrying the pile threads, means for crossing a pair of

- normally parallel ground warp threads with the lay in a rearmost position, means for moving the lay forward to keep the ground warp threads crossed in front of the lay, 5 means for passing the pile thread between the crossed ground warp thread in front of the lay, means for uncrossing the ground warp threads, means for beating up the pile thread by the lay, means for passing the 10 pile thread between the parallel ground warp threads in front of the lay for completing the knot, means for cutting the pile thread between the fabric and the tuft yarn tube while the latter is in a lowermost and 15 rearward position, and means for successively introducing sets of weft threads to bind the ground warp threads and the reinforcing weft threads.
26. A pile fabric loom for interweaving 20 ground warp threads, pile threads and weft threads, provided with coöperating elements, namely, an intermittently reciprocating lay, an intermittently operating shogging device for the ground warp threads, heddles for the 25 ground warp threads, endless carrier chains carrying sets of tuft yarn tubes, and an actuating device for removing a set of tuft yarn tubes from the said carrier chains and for passing each tube of the set of the 30 removed tuft yarn tubes twice between pairs of the ground warp threads to form Persian knots on pairs of ground warp threads.
27. A pile fabric loom for interweaving 35 ground warp threads, pile threads and weft threads, provided with coöperating elements, namely, an intermittently reciprocating lay, an intermittently operating shogging device for the ground warp threads, heddles for the ground warp threads, endless carrier 40 chains carrying sets of tuft yarn tubes, a cutting device for cutting the pile threads, and an actuating device for removing a set of the said tuft yarn tubes from the said carrier chains, for passing each tube of the 45 set of the removed tuft yarn tubes twice between pairs of the ground warp threads to form Persian knots on pairs of ground warp threads, and for returning the set of removed tuft yarn tubes to the endless carrier 50 chains after the knots are formed and the pile threads are cut.
28. A pile fabric loom for interweaving 55 ground warp threads, reinforcing warp threads, sets of weft threads and pile threads, provided with coöperating elements, namely, an intermittently reciprocating lay, an intermittently operating shogging device for the ground warp threads, heddles for the ground warp threads, a set 60 of tuft yarn tubes, an actuating device for the said tuft yarn tubes to pass each of the said tubes twice between the pairs of the ground warp threads, once while the same are crossed and then while the ground warp threads are in normal or parallel position, a 65 cutting device for the pile threads, sets of plain yarn tubes carrying the reinforcing warp threads, means for operating the said plain yarn tubes in unison with the heddles, and weft carriers for introducing sets of 70 weft threads for binding the ground warp threads and the reinforcing warp threads.
29. A pile fabric loom having endless carrier chains, sets of tuft yarn tubes held removably thereon, an intermittently reciprocating lay, a shogging device and an actuating mechanism for removing a set of tuft yarn tubes from the said endless carrier chains and for imparting first a downward motion then a simultaneous rearward and 75 downward motion, then a downward motion, then an upward motion, then a forward motion, then an upward motion, and then a simultaneous downward and rearward motion.
30. A pile fabric loom having endless carrier chains, sets of tuft yarn tubes held removably thereon, an intermittently reciprocating lay, a shogging device, and an actuating mechanism for removing a set of 80 tuft yarn tubes from the said endless carrier chains and for imparting first a downward motion, then a simultaneous rearward and downward motion, then a downward motion, then an upward motion, then a forward 85 motion, then an upward motion, then a simultaneous downward and rearward motion and then a straight downward motion to the lowermost position of rest.
31. A pile fabric loom having endless carrier chains, sets of tuft yarn tubes held removably thereon, an intermittently reciprocating lay, a shogging device, and an actuating mechanism for removing a set of tuft 90 yarn tubes from the said endless carrier chains and for imparting first a downward motion, then a simultaneous rearward and downward motion, then a downward motion, then an upward motion, then a forward 95 motion, then an upward motion, then a simultaneous downward and rearward motion and then a straight downward motion to the lowermost position of rest.
32. A pile fabric loom provided with a set of tuft yarn tubes carrying pile threads, an actuating mechanism for the said set of tuft 100 yarn tubes to move the latter down between the ground warp threads a distance from the fell of the fabric and to hold the said tuft 105 yarn tubes at rest in the said lower position, and a cutting mechanism for cutting the pile threads while so held at a point between the 110 fell of the fabric and the said tuft yarn tubes.
33. A pile fabric loom provided with an

endless carrier chain, sets of tuft yarn tubes held removably thereon, and an actuating mechanism for the said set of tuft yarn tubes and having vertical slides movable up 5 and down, longitudinal slides movable longitudinally on the said vertical slides, bars 10 slideable transversely in the said longitudinal slides and adapted to engage the said set of tuft yarn tubes to move the same from the said carrier chains, to manipulate the tuft 15 yarn tubes during the formation of the knot and to return the tuft yarn tubes to the said endless carrier.

34. A pile fabric loom provided with an endless carrier chain, sets of tuft yarn tubes held removably thereon, and an actuating mechanism for the said set of tuft yarn tubes and having vertical slides movable up and down, longitudinal slides movable 20 longitudinally on the said vertical slides, bars slideable transversely in the said longitudinal slides, means for moving the said bars periodically in a transverse direction, means for moving the vertical slides periodically 25 cally up and down, and means for moving the longitudinal slides periodically forward and backward.

35. A pile fabric loom provided with an endless carrier chain, sets of the tuft yarn tubes held removably thereon, and an actuating mechanism for the said set of tuft 30 yarn tubes and having vertical slides movable up and down, longitudinal slides movable longitudinally on the said vertical 35 slides, bars slideable transversely in the said longitudinal slides, cam mechanisms for the said bars, the vertical slides and the horizontal slides, and a revoluble cam shaft carrying the cams of the said cam mechanisms.

40 36. A pile fabric loom comprising an intermittently reciprocating lay, a set of tuft yarn tubes carrying pile threads for forming Persian knots on pairs of ground warp threads, shogging combs for the ground 45 warp threads and having transverse sliding movement, one of the combs also having an up and down movement, and heddles for the ground warp threads.

37. A pile fabric loom comprising an intermittently reciprocating lay, a set of tuft 50 yarn tubes carrying pile threads for forming Persian knots on pairs of ground warp threads, shogging combs for the ground warp threads and having transverse sliding movement, one of the combs also having an up and down movement, heddles for the ground warp threads, and a reed for the passage of the ground warp threads and interposed between the shogging combs.

60 38. A pile fabric loom comprising an intermittently reciprocating lay, a set of tuft 125 yarn tubes carrying pile threads for forming Persian knots on pairs of ground warp threads, shogging combs for the ground

warp threads and having transverse sliding movement, one of the combs also having an up and down movement, heddles for the ground warp threads, two sets of yarn tubes carrying reinforcing warp threads and moving in unison with the said heddles, weft 70 threads carrying needles for carrying sets of weft threads through the open shed from one side of the machine, a shuttle moving periodically up and down on the other side of the machine and operating in conjunction with 75 the said needles for forming a selvage with the said weft threads, a revoluble cam shaft, and mechanism connecting the said cam shaft with the said devices to operate the same in the proper sequence. 80

39. A pile fabric loom having a shogging device comprising shogging combs, means for periodically moving the shogging combs transversely in opposite directions, and means for moving one shogging comb periodically toward and from the other. 85

40. A pile fabric loom for weaving pile knots on pairs of ground warp threads, provided with an intermittently reciprocating lay, means for holding the lay at rest for 90 a time on the pile knot formed, and heddles, and means for actuating the said heddles for changing the position of the ground warp threads during the time the lay is at rest on the pile knots, to prevent loosening of the 95 pile knots.

41. A pile fabric loom for forming pile knots on pairs of ground warp threads, provided with a lay having alternating long and short dents, and a pair of oppositely 100 disposed shogging combs for shifting the ground warp threads in approximately the same plane, to allow the short dents of the lay to readily pass between a pair of crossed ground warp threads. 105

42. A pile fabric loom for forming pile knots on pairs of ground warp threads, provided with tuft yarn tubes carrying pile threads for forming the pile knots on the ground warp threads, an intermittently reciprocating lay, and a shogging device for moving the ground warps successively into crossed and uncrossed positions in approximately the same horizontal plane, means for passing the said tuft yarn tubes between the 115 ground warp threads first when they are crossed and again when they are uncrossed, the said lay beating up the half pile knot first formed and then the remainder of the complete pile knot. 110

43. A pile fabric loom for forming pile knots on pairs of ground warp threads, provided with tuft yarn tubes carrying pile threads for forming the pile knots, an intermittently reciprocating lay having alternate long and short dents, a shogging device for crossing and uncrossing the said ground warp threads, and means for causing 120 125

the said lay to beat up the half pile knot first formed and while the ground warp threads are in an uncrossed position and the pile thread extends transversely from one ground warp thread to the other to be engaged by the said short dents.

In testimony whereof I have signed my

name to this specification in the presence of two subscribing witnesses.

JAMES KARMI DALKRANIAN.
